REGULATING SYSTEM

Cyril C. Levy, Pittsburgh, Pa., assignor to Westinghouse Electric Corporation, East Pittsburgh, Pa., a corporation of Pennsylvania

Application April 27, 1944, Serial No. 533,083

8 Claims. (Cl. 314—64)

This invention relates to a control system and in particular to regulating systems for arc furnace regulators.

Electronic regulating systems have been employed heretofore for controlling the operation of reversible motors in response to predetermined changes in operating conditions of the system with which the motor is employed. In practice, it has been found that in such systems utilizing a plurality of sets of electronic tubes for controlling the reversing of the motor, that although as a general rule one set of the tubes conducts while the other set is nonconducting, there also develops a condition in which the conducting period is transferred immediately from one set of tubes to the other set of tubes, thereby causing hunting in the regulating system. Further, where such systems have been employed for arc furnace regulation, considerable overrun has often been encountered to the detriment of the electrodes.

An object of this invention is to provide an electronic regulating system having a controllable dead zone of operation for preventing hunting.

Another object of this invention is to provide a simple and highly sensitive electric discharge regulating system for effecting a sensitive control of the operation of a reversible direct-current feed motor in accordance with predetermined conditions in an associated alternating-current load circuit while preventing hunting.

A further object of this invention is to provide an electronic regulating system having anti-hunting characteristics and dynamic braking for controlling the operation of a reversible motor.

Other objects of this invention will become apparent from the following description when taken in conjunction with the accompanying drawing, the single figure of which is a diagrammatic view of an arc furnace regulating system embodying the teachings of this invention.

Referring to the drawing, an electric furnace 10 is illustrated, the furnace comprising a receptacle 12 containing a bath of metallic material 14 and three movable electrodes 16, 18, and 20. The electrodes 16, 18, and 20 are connected by conductors 22, 24, and 26, respectively, through the transformer 28 to the three-phase supply circuit comprising conductors 30, 32, and 34.

Each of the movable electrodes is provided with a reversible motor for raising and lowering it and an electronic regulating system for governing the operation of the motor in accordance with predetermined changes in the current flowing through the electrode and the potential across the electrode arc. Since the electronic regu-

lating system associated with each of the motors is of like construction and operates in the same manner, only one of the regulating systems and motors for controlling the positioning of the electrodes is illustrated.

In the drawing a reversible motor 36 comprising an armature 38 and a separately excited field winding 40 is illustrated for raising and lowering the electrode 20. The armature 38 is mechanically connected to the electrode 20 in any suitable manner for effecting movement thereof and in the embodiment illustrated is connected by the shaft 42, a winding drum 44 and a flexible conductor 46 which passes over the pulley 48.

In order to control the energy in the load circuit, suitable means may be provided for controlling the direction and amount of current flowing through the armature 38 of the motor 36 to control the position of the electrode 20. In the embodiment illustrated the electric discharge devices 50, 52 and 54, 56 are connected in paired relation in a well known manner so as to provide for complete rectification of the alternating current from the source of supply 30, 32, and 34 to supply a unidirectional current to the motor 36 in a predetermined direction.

Thus the anodes 58 and 60 of the discharge devices 50 and 52 are connected to the terminals of secondary winding 62 of the control transformer 64 and anodes 66 and 68 of the discharge devices 54 and 56 are connected to the terminals of secondary winding 70 of the control transformer, the primary winding 72 of which is connected across supply conductors 30 and 32. The cathodes 74 and 76 of discharge devices 50 and 52 are connected by conductor 78 to conductor 80 and one side of the armature 38, the other side of the armature being connected by conductor 82 through resistor 84 to the mid or center tap 86 of the secondary winding 62. Likewise the cathodes 88 and 90 of discharge devices 54 and 56 are connected by conductor 92 to conductor 82 and one side of the armature 38, the other side of the armature being connected by conductor 80 through resistor 94 to the center tap 96 of the secondary winding 70.

As illustrated, provision is made to control the bias of grids 98, 100 and 102, 104 of the pairs of discharge devices 50, 52 and 54, 56 respectively in accordance with the current and voltage conditions of the load circuit to control the value and direction of current supplied to the motor 36 from the alternating-current source. For this purpose a current transformer 106 is disposed in conjunction with conductor 26 for applying to

a suitable rectifying means such as the rectifying bridge circuit 108 a control voltage which is responsive to the current in the load circuit. The direct-current terminals of the bridge circuit 108 are connected to a control resistor 110 so as to apply thereto the direct-current voltage. A rectifying means such as the rectifying bridge circuit 112 is connected to conductor 26 by conductor 114 and by conductors 116 and 118 to the receptacle 12 whereby a control voltage which is a measure of the potential of the electrode arc is impressed thereacross. The direct-current terminals of the bridge circuit 112 are connected to a control resistor 120 so as to apply the resulting direct-current voltage thereto.

A potential transformer 122 having its primary winding connected to the supply conductors 30 and 32 is also connected to a rectifying bridge circuit 124 for applying a voltage proportional to the voltage of the constant supply circuit across a control resistor 126 of the control circuit. Connected in series circuit with the series connected resistors 110, 120, and 126 is another control resistor 128 disposed to have a voltage applied thereto from a rectifying device such as the tube 130 which is connected through potential transformer 138 across the supply conductors 30 and 32. The direct-current voltage across the different control resistors 110, 120, 126, and 128 are of different predetermined polarity, the purpose of which will be explained more fully hereinafter.

The tube 130 is of the type having two anodes 134 and 136 connected to the secondary winding of transformer 138, the center tap 140 of which is connected to one end of control resistor 128, a cathode 142 connected to the other end of control resistor 128, and two grids 144 and 146 disposed to control the output of the tube. In order to control the amplitude of the grid voltage on the grids 144 and 146 an amplitude control circuit 148 is provided.

The amplitude control circuit comprises a bridge formed of two impedances 150 and 152 and two saturable reactors 154 and 156 having their direct-current secondary windings connected in series, the bridge circuit being connected by conductors 158 and 160 to the supply conductors 30 and 32 through the variable condenser 162. The direct-current secondary windings of the reactors 154 and 156 are connected by conductors 157 and 159 across the series connected control resistors 110, 120, and 126 whereby the voltage derived therefrom is impressed across the secondary windings to control the impedance of the reactors. As illustrated, the bridge circuit is connected to the primary winding of a grid transformer 164, the terminals of the secondary winding of which are connected to the grids 144 and 146 and a center tap of which is connected through the parallel connected capacitor 166 and resistor 168 to the cathode 142.

A similar control circuit is provided for controlling the bias of grids 102 and 104 of tubes 54 and 56 to control the operation of the motor 36. As in the case of tubes 50 and 52, control resistors 170, 172, 174, and 176 are connected in series circuit relation with each other in the grid circuit of tubes 54 and 56. The control resistors 170, 172, 174, and 176 are disposed to have a direct-current voltage impressed thereon in response to the electrode current, arc potential, constant source of supply, and the output of rectifying tube 178, respectively. For this purpose, current transformer 180 is disposed in conjunction with

conductor 26 to supply the rectifying bridge 102 and consequently the control resistor 170 with a voltage proportional to the current in the load circuit; the rectifying bridge 184 is connected across the electrode arc for supplying a direct-current voltage to resistor 172 which is proportional to the electrode potential; and the resistor 174 is connected across a rectifying bridge 188 through potential transformer 188 to supply conductors 30 and 32.

The direct-current voltage applied to control resistor 176 is determined by the output of tube 180 which, similarly to tube 130, is provided with two anodes 190, 192 connected to the terminals of the secondary winding of a potential transformer 194, the center tap of which is connected to one end of the control resistor 176, a cathode 196 connected to the other end of control resistor 176 and two grids 198 and 200 disposed to control the output of the tube. The primary winding of the transformer 194 is connected across supply conductors 30 and 32.

The amplitude of the grid voltage on the grids 198 and 200 of tube 180 is controlled by the amplitude control circuit 202 which comprises the bridge formed of two impedances 204 and 206 and two saturable reactors 208 and 210, the bridge being connected through a variable capacitor 212 to supply conductors 30 and 32. The secondary windings of the reactors 208 and 210 are connected in series and are connected by conductors 214 and 216 across the series connected control resistors 170, 172, and 174 whereby the differential voltage thereof is impressed on the direct-current windings of the reactors to control the impedance thereof. The bridge is also connected to a grid transformer 218, the secondary winding of which is connected to the grids 198 and 200 and the center tap of which is connected through the parallel connected capacitor 220 and resistor 222 to the cathode 196.

The direct-current voltage impressed across the different control resistors 170, 172, and 174 have different polarities depending upon the rectifying bridges used for translating the alternating current to direct current. In the embodiment illustrated the direct-current voltages which are proportional to the voltage of the supply and proportional to the arc potential, that is, the direct-current voltage across resistors 174 and 172, respectively, are additive and oppose the direct-current voltage across resistor 170 which is proportional to the current in the load conductor.

In the case of control resistors 110, 120, and 126 in circuit with the grids of tubes 50 and 52, the voltage across resistor 110 which is proportional to the current in the load circuit is of opposite polarity to the voltage across resistor 120 which is proportional to the arc voltage and the voltage across resistor 126 which is proportional to the voltage of the constant supply. In the case of both control resistors 128 and 176, the voltages across which are controlled by tubes 130 and 178, respectively, the voltages are of the same polarity as those across control resistors 126 and 174, respectively, for placing a negative bias on the grids of each pair of tubes 50, 52, and 54, 56 when the tubes 130 and 178 are functioning to impress a voltage across the control resistors 128 and 176, respectively.

In order to provide for braking the motor 36 to prevent overrun thereof, electronic dynamic braking circuits are provided. As illustrated, a tube discharge device 224 having an anode 226, a cathode 228 and a grid 230 and a tube discharge

device 232 having an anode 234, a cathode 238 and a grid 230 are connected in circuit relation with the conductors 80 and 82 to give the required braking. The tube 224 has its cathode 228 connected to conductor 82 on one side of resistor 84, the grid 230 of the tube being connected through the battery 240 to the other side of resistor 84, the anode 226 being connected through resistor 242 to conductor 78 and from thence to conductor 80. Likewise, the tube 232 has its cathode 236 connected to conductor 80 on one side of resistor 94, the grid 238 of the tube being connected through the battery 244 to the other side of resistor 94, the anode being connected through resistor 246 to conductor 92 and from thence to conductor 82. The operation of the dynamic braking circuits will be described hereinafter.

In operation, assuming that supply conductors 30, 32, and 34 are connected to a suitable constant source of alternating-current power (not shown), transformer 28 for supplying the load is energized. At the same time transformer 64 for supplying power to the motor 38 and control transformers 122, 138, 194, and 188 are energized. Since there is no current flowing in the load circuit, there is no voltage across either of the control resistors 110 or 170, nor is there voltage across either of the control resistors 120 or 172 since there is no arc. However, there is voltage across control resistors 126 and 174 proportional to the voltage of the constant source, the voltage across resistors 126 and 174 being so small by design, however, as to be considered as negligible with respect to voltages impressed under predetermined conditions across the other control resistors. The voltage across the resistors 126 and 174 is by design of such a polarity as to place a negative bias on the grids of the pairs of tubes 50, 52 and 54, 56, respectively.

The transformers 138 and 194 are connected to supply power to the rectifier tubes 130 and 178, respectively, the output of which is controlled by the impedance of the amplitude bridge circuits 148 and 202, respectively. As illustrated, with the bridges connected across the source of supply and when the system is initially energized, the only source of supply for the direct-current secondary windings of the reactors of the bridge circuits is the small negligible direct-current voltage across resistors 126 and 174. Under these conditions, the impedance of each of the amplitude bridge circuits is a maximum, with the result that the voltage on the grid transformers 164 and 218 is negligible, and the alternating-current component applied to the grids of tubes 130 and 178 is negligible, and the tubes operate at maximum output to give a large direct-current voltage across control resistors 128 and 176, respectively. The voltage thus applied to resistors 128 and 176 is of the same polarity as that across resistors 126 and 174, respectively, and, therefore, co-operate therewith to positively place a negative bias on the grids of control tubes 50, 52 and 54, 56 to prevent operation of the motor 36.

When the electrodes 16, 18, and 20 are manually lowered to a position where an arc is struck, the maximum arc potential is established and a direct-current voltage which is proportional thereto is impressed across control resistors 120 and 172. Since the polarity of the direct-current voltage across resistor 120 is the same as that across resistors 126 and 174 when the arc is first established, a large negative bias is applied to the grids 98 and 100 of tubes 50 and 52 through the 78

circuit extending from the control grids 98 and 100 through conductor 99, control resistors 110, 120, 126, 128 and conductor 101 to the cathodes 74 and 76. Since the bias of the grids is negative, the tubes 50 and 52 are blocked.

However, the polarity of the direct-current voltage across resistor 172 opposes that across resistors 174 and 176. Since the direct-current voltage across resistor 172 is larger than that across resistor 174, the latter voltage being negligible as stated hereinbefore, a direct-current voltage which is the differential of the voltages across resistors 172 and 174 is impressed across the direct-current secondary windings of the reactors 210 and 208 of the amplitude bridge control circuit 202 to decrease the impedance of the bridge circuit and consequently increase the voltage on the grid transformer 218 connected in circuit therewith. This increase in voltage across the primary windings of the grid transformer 218 increases the amplitude of the alternating-current component of the voltage on the grids 198 and 200 of tube 180 to decrease the output therefrom and decrease the direct-current voltage applied across control resistor 176. Since the direct-current voltage applied to the secondary windings of reactors 210 and 208 is a maximum under the conditions described when the arc is first established, the amplitude bridge control circuit 202 functions to control tube 178 to substantially prevent the impressing of a direct-current voltage across resistor 176. Under these conditions the differential of the direct-current voltages across the control resistors 170, 172, 174, and 176 is such that the bias of grids 102 and 104 of motor control tubes 54 and 56 is rendered less negative through the circuit extending from the control grids 102 and 104 through conductor 248, control resistors 170, 172, 174, 176 and conductor 250 to the cathodes 88 and 90. The control grids 102 and 104 thus being made positive with respect to the cathodes 88 and 90, the tubes 54 and 56 are alternately rendered conductive when their anodes are positive with respect to their cathodes. 45 When tubes 54 and 56 are thus rendered conductive, a fully rectified direct current is supplied to the armature 38 of motor 36 through the circuit extending from the center tap 96 of the secondary winding 70 of the transformer 64, through resistor 94, conductor 80, armature 38, conductor 82, conductor 92, cathodes 88 and 90 and anodes 66 and 68 of the tubes 54 and 56, respectively, back to the terminals of the secondary winding 70. The feed motor 36 then operates to feed the electrode 20 towards the metal 14 at a relatively high speed as the voltage applied to the grids 102 and 104 is a maximum.

As the electrode 20 approaches the metal 14, the arc potential decreases and consequently the direct-current voltage applied to control resistors 120 and 172 decreases while the current in the load conductor 28 increases with a resulting increase in the direct-current voltage applied to control resistors 110 and 170. As the differential of the direct-current voltages across resistors 170, 172, and 174 approaches zero, the differential voltage impressed across the direct-current secondary windings of reactors 210 and 208 also approach zero to effect an increase in the impedance of the amplitude bridge circuit 202 and control the operation of tube 180 to impress a direct-current voltage across control resistor 176, the direct-current voltage being of the polarity, as referred to hereinbefore, to place a negative bias on the control grids 102 and 104 of tubes 54 and

56 to block them from passing current. The amplitude bridge control circuit 202 thus anticipates the correct positioning of the electrode 20 to prevent hunting.

During the period of time that motor control tubes 54 and 56 are conducting current to effect the operation of the motor 36 to lower the electrode 20, the current flows through the resistor 94 and the voltage drop thereacross is sufficient to overcome the effect of battery 244 and render the bias of grid 238 of discharge device 232 negative and block the tube from conducting. However, when the tubes 54 and 56 are blocked and current ceases to flow through resistor 94, the battery 244 functions to render the bias on grid 238 positive and permit the tube 232 to pass current. Under these circumstances, the counterelectromotive force of the motor 36 is utilized to provide dynamic braking for the motor 36, current flowing from the armature 38 through conductor 80, cathode 236, anode 234, resistor 248, conductor 92 and conductor 82 to the other side of the armature 38. The dynamic braking thus provided quickly stops the motor 36 and prevents further lowering or overrun in positioning the electrode.

Under conditions of equilibrium where the electrodes are positioned for ideal operation, the direct-current voltages across resistors 110 and 170 which are proportional to the current flowing in the conductor 26 and the direct-current voltages across resistors 120 and 172 which are proportional to the arc voltage are in substantial balance and the direct-current voltage across each of resistors 128 and 176 is sufficient and of the correct polarity to prevent firing of either of the pairs 50, 52 and 54, 56 of motor control tubes. In fact, in approaching such ideal positioning of the electrode 20, the voltages across resistors 128 and 176 are of such magnitude as to effectively block the control tubes 50, 52 and 54, 56. The amplitude bridge control circuits 148 and 202 thus provide a positive dead zone in the operation of the pairs 50, 52 and 54, 56 of motor control tubes, thereby preventing the immediate transfer of firing from one set or pair of tubes to the other except in cases where a positive short circuit such as where a cave-in of the metal 14 about and in contact with the electrode 20 is encountered.

If a short circuit is encountered as referred to while the motor is operating to lower the electrode 20, the direct-current voltage applied to control resistors 110 and 170 immediately becomes a maximum and that applied to control resistors 120 and 172 becomes a minimum with opposite effects on the operation of the pairs 50, 52 and 54, 56 of motor control tubes. Under these conditions, the direct-current voltage across resistor 170 is of the same polarity as the voltages across resistors 174 and 176 to overcome the direct-current voltage, if any, across resistor 172 and place a negative bias on the grids 102 and 104 to block the tubes 54 and 56 from conducting.

When the direct-current voltage across resistor 110 is increased as described, the differential voltage of the direct-current voltages across control resistors 110, 120, and 126 is impressed across the direct-current secondary windings of the reactors 154 and 156 of the amplitude bridge control circuit 148 to decrease the impedance of the bridge circuit and consequently increase the voltage on the grid transformer 164 connected in circuit therewith. This increase in voltage functions to increase the amplitude of the alternating-current component of the voltage on the grids 144 and

146 of tube 130 to decrease the output therefrom and decrease the direct-current voltage applied across control resistor 128. As the direct-current voltage applied to resistor 110 is a maximum and the direct-current voltage applied to resistors 120, 126 and 128 are at a minimum and of opposite polarity to that across resistor 110, a positive bias is applied to the grids 98 and 100 of motor control tubes 50 and 52, respectively, through the circuit extending from the control grids 98 and 100 through conductor 99, control resistors 110, 120, 126, 128 and conductor 101 to the cathodes 74 and 76. The control grids 98 and 100 thus being made positive with respect to the cathodes 74 and 76, the tubes 50 and 52 are alternately rendered conductive when their anodes are positive with respect to their cathodes.

With the tubes 50 and 52 conductive, a fully rectified direct current is supplied to the armature 38 of motor 36 through the circuit extending from the center tap of the secondary winding 62 of the transformer 64, through resistor 84, conductor 82, armature 38, conductor 80, conductor 78, cathodes 74 and 76 and anodes 88 and 80 of the tubes 50 and 52, respectively, back to the terminals of the secondary winding 62. The feed motor 36 then operates to raise the electrode away from the metal 14 to a position where the direct-current voltage across the control resistors 110, 120, 126 and 170, 172, 174 are again in substantial equilibrium and the direct-current voltage across each of control resistors 128 and 176 effects a negative bias on the grids of control tubes 50, 52 and 54, 56.

In raising the electrode 20 as just described, dynamic braking is also provided when tubes 50 and 52 cease to conduct, and current ceases to flow through resistor 84. When this happens, the battery 240 places a positive bias on the grid 230 of tube 224 to render it conductive whereby the counterelectromotive force of the motor 36 effects the dynamic braking. With the tube 224 conductive, a circuit is completed extending from the armature 38 through conductor 82, cathode 228, anode 226, resistor 242, conductor 78 and conductor 80 back to the armature 38 to effectively brake the motor 36.

The system of this invention is very sensitive as to changes in operating conditions and provides for a quick correction in the positioning of the electrodes. By utilizing the amplitude bridge control circuits in the manner described, provision is made for the prevention of hunting in the operation or firing of the motor control tubes, the bridge circuits ensuring a period of nonconductivity in transferring the control circuits from one pair of control tubes to the other for all operations except that where a direct short circuit is encountered. Further, the provision of dynamic braking as described prevents an overrun in the positioning of the electrodes thereby preventing excessive operation of the motor to adjust the position of the electrodes.

While this invention has been described with reference to a particular embodiment thereof, it is, of course, not to be limited thereto except in so far as is necessitated by the scope of the appended claims.

70 I claim as my invention:

1. In a control system, in combination, a reversible motor, a plurality of pairs of electric valves disposed to selectively connect the motor to a source of alternating current to control the speed and direction of operation of the motor, a control

circuit associated with each pair of electric valves, each of the control circuits including a pair of sources of control voltages variable in opposite senses and a source of control voltage variable in response to changes in the pair of control voltages of opposite senses, the variable control voltage being of a polarity to render the valves associated therewith non-conducting when the pair of variable control voltages of opposite senses are in substantial balance.

2. In a control system, in combination, a reversible motor, a plurality of pairs of electric valves having grids for controlling the conductivity thereof disposed to selectively connect the motor to a source of alternating current to control the speed and direction of operation of the motor, a control circuit associated with each pair of electric valves for controlling the bias of the grids of the valves, each of the control circuits including a pair of sources of control voltages variable in opposite senses and a source of control voltage variable in response to changes in the pair of control voltages of opposite sense, the variable control voltage being of a polarity to render the valves associated therewith non-conducting when the pair of variable control voltages of opposite senses are in substantial balance.

3. In a control system for regulating the feeding of an electrode for producing and maintaining an electric arc, the combination comprising, a motor which is to be regulated, a plurality of pairs of electric valves having grids for controlling the conductivity thereof disposed to selectively connect the motor to a source of alternating current to control the speed and direction of operation of the motor, a control circuit associated with each pair of electric valves for controlling the bias of the grids of the valves, each of the control circuits including a pair of variable sources of control voltage, the voltage of one of the pair of sources being of opposite polarity to the voltage of the other one of the pair of sources, and means including a variable control voltage which is responsive to and controlled by the differential of the pair of sources of control voltages to render the valves associated therewith nonconducting when the control voltages of the pair of sources are in substantial balance.

4. In a control system, in combination, a reversible motor, a plurality of pairs of electric valves disposed to selectively connect the motor to a source of alternating current to control the speed and direction of operation of the motor, a control circuit associated with each pair of electric valves, each of the control circuits including a pair of sources of control voltages variable in opposite senses and a source of variable control voltage, the source of variable control voltage including an electric valve, a saturable reactor connected in circuit relation therewith, the saturation of the reactor being responsive to the differential of the pair of control voltages of opposite senses to control the output from the control voltage electric valve, the variable control voltage being of a polarity to render the valves associated with the control circuit non-conducting when the pair of variable control voltages of opposite senses are in substantial balance.

5. In a control system for regulating the feeding of an electrode for producing and maintaining an electric arc, the combination comprising, a motor which is to be regulated, a plurality of pairs of electric valves having grids for controlling the conductivity thereof disposed to selectively connect the motor to a source of alternating current to control the speed and direction of operation of the motor, a control circuit associated with each pair of electric valves for controlling the bias of the grids of the valves, each of the control circuits including a pair of sources of control voltages variable in opposite senses and a source of control voltage vari-

ing current to control the speed and direction of operation of the motor, a control circuit associated with each pair of electric valves for controlling the bias of the grids of the valves, each of the control circuits including a pair of sources of control voltage variable in opposite senses and a secondary source of variable control voltage, the secondary source of variable control voltage including an electric valve, a saturable reactor connected in circuit relation therewith, the saturation of the reactor being responsive to the differential of the pair of sources of control voltages to control the output from the control voltage electric valve, the secondary source of variable control voltage being of a polarity to render the valves associated with the control circuit non-conducting when the pair of variable sources of control voltages of opposite senses are in substantial balance.

6. In a control system, in combination, a reversible motor, a plurality of pairs of electric valves disposed to selectively connect the motor to a source of alternating current to control the speed and direction of operation of the motor, a control circuit associated with each pair of electric valves, each of the control circuits including a pair of sources of control voltages variable in opposite senses and a source of control voltage variable in response to changes in the pair of control voltages of opposite senses, the variable control voltage being of a polarity to render the valves associated therewith nonconducting when the pair of variable control voltages of opposite senses are in substantial balance, and means comprising an electric valve associated with each pair of control electric valves and connected in circuit relation with the motor to provide dynamic braking for the motor when the associated pair of control electric valves are rendered nonconducting to stop the motor.

7. In a control system, in combination, a reversible motor, a plurality of pairs of electric valves disposed to selectively connect the motor to a source of alternating current to control the speed and direction of operation of the motor, a control circuit associated with each pair of electric valves, each of the control circuits including a pair of sources of control voltages variable in opposite senses and a source of variable control voltage including an electric valve, a saturable reactor connected in circuit relation therewith, the saturation of the reactor being responsive to the differential of the pair of control voltages of opposite senses to control the output from the control voltage electric valve, the variable control voltage being of a polarity to render the valves associated with the control circuit nonconducting when the pair of variable control voltages of opposite senses are in substantial balance, and means comprising an electric valve associated with each pair of control electric valves and connected in circuit relation with the motor to provide dynamic braking for the motor when the associated pair of control electric valves are rendered nonconducting to stop the motor.

8. In a control system, in combination, a reversible motor, a plurality of pairs of electric valves disposed to selectively connect the motor to a source of alternating current to control the speed and direction of operation of the motor, a control circuit associated with each pair of electric valves, each of the control circuits including a pair of sources of control voltages variable in opposite senses and a source of control voltage vari-

able in response to changes in the pair of control voltages of opposite senses, the variable control voltage being of a polarity to render the valves associated therewith nonconducting when the pair of variable control voltages of opposite senses are in substantial balance, and a pair of dynamic braking circuits for the motor, each of the dynamic braking circuits including a resistor connected in the motor circuit between the motor and a pair of the electric valves to have a control voltage thereacross when the pair of electric valves are conducting and another electric valve associ-

ated with the pair of electric valves disposed to be connected across the motor and to be controlled by the control voltage across the resistor, said another electric valve being rendered nonconducting when the pair of electric valves are conducting and conducting when the pair of electric valves are nonconducting to thereby reverse the current flow to the motor and effect the dynamic braking thereof when the pair of electric valves are rendered nonconducting.
